Hubert Dalton Inventor

By his Attorney

J. M. Miller, A. L. Miller

UNITED STATES PATENT OFFICE.

HUBERT DALTON, OF NEW YORK, N. Y., ASSIGNOR TO DALTON MANUFACTURING CORPORATION, A CORPORATION OF NEW YORK.

DESIGN FOR A LATHE CABINET-STAND.

51,897.

Specification for Design.

Patented Mar. 26, 1918.

Application filed October 23, 1917. Serial No. 198,177. Term of patent 14 years.

To all whom it may concern:

Be it known that I, HUBERT DALTON, a citizen of the United States, residing at New York, in the county of New York and State of New York, have invented a new, original, and ornamental Design for a Lathe Cabinet-Stand, of which the following is a specification, reference being had to the

accompanying drawing, forming a part thereof.

In this drawing Figures 1 and 2 are front and side elevations respectively.

I claim:

The ornamental design for a lathe cabinet stand as shown.

HUBERT DALTON.
